CLAIM

I claim the ornamental design for a "light bar," as shown and described.

DESCRIPTION

FIG. 1 is a perspective view of a light bar attached to a music stand.

FIG. 2 is a top perspective view of the light bar shown in FIG. 1.

FIG. 3 is a left side view of the light bar shown in FIG. 2.

FIG. 4 is a front side view of the light bar shown in FIG. 2.

FIG. 5 is a bottom side view of the light bar shown in FIG. 2.

FIG. 6 is a rear side view of the light bar shown in FIG. 2.

FIG. 7 is a right side view of the light bar shown in FIG. 2; and,

FIG. 8 is a top side view of the light bar shown in FIG. 2.

The broken lines shown in dashed form are only for illustrative purposes to show visible environmental structure and form no part of the claimed design.

The music stand shown in broken lines in FIG. 1 is included for illustrative purposes only and forms no part of the claimed design.

The break lines do not exist in reality in the light bar embodying the design and are only for illustrative purposes to show bounds of the claimed design. It is understood that the claimed design extends to the break lines but does not include the break lines. The appearance of any portion of the light bar between the break lines forms no part of the claimed design.
